UNITED STATES PATENT OFFICE.

DONALD H. HERBERT, OF SPOKANE, WASHINGTON.

WOODWORKING MACHINE.

Application filed April 8, 1924. Serial No. 704,933.

My present invention relates to improvements in woodworking machines especially designed for boring and cutting pockets and mortises in window sash rails for the accommodation of the sash cords thereof.

The primary object of my invention is the provision of means whereby the above indicated operations may be accomplished with facility, rapidity, and accuracy, and in which the parts may quickly be adjusted in the machine for adaptation to various sizes of stock or material.

The invention involves the use of rotary boring and cutting tools, and feed mechanism, all of which are compactly arranged and driven from a single source of power, and by means of which the stock or sash rails are automatically fed, successively to the several machine tools, and after being operated upon the finished rails are discharged from the machine.

The stock or rails are fed automatically in a vertical plane to the machine and transferred or moved laterally and intermittently across the machine during the operation of the machine tools, and are positively retained and guided, until the completed articles are delivered.

Means are provided for adjusting the feed mechanism to various sizes of stock, and for adjusting the boring bits and rotary cutting heads, as will be hereinafter more fully pointed out.

In the accompanying drawings I have illustrated one complete example of the physical embodiment of my invention applied to a sash-rail machine, but it will be understood that the machine is adapted for use in connection with other structures to be bored and drilled. In the drawings the elements of the machine are combined and arranged according to the best mode I have thus far devised for the application of the principles of my invention.

Figure 1 is a view in side elevation of a machine embodying my invention, the hopper being adjusted for short length rails.

Figure 2 is a view in elevation of the machine looking from the left end in Figure 1.

Figure 3 is an end elevation of the machine looking from the right in Figure 1.

Figure 4 is a view in elevation from the rear side of Figure 1, parts of the machine being omitted for convenience of illustration.

Figure 5 is a detail view in perspective

showing the cam shaft and operating cams thereon for actuating the several parts of the machine.

Figure 6 is a top plan view of the machine.

Figure 7 is a detail perspective view of one of the control bars and its connections for the stock or rails.

Figures 8 and 9 are perspective views of portions of rails that have been operated on by the machine.

As an aid in understanding the utility and operation of the machine reference may first be had to Figures 8 and 9 of the drawing where the rails 1 and 2 are shown, each having a longitudinally extending groove 3 and a transversely extending pocket 4. In Figure 8 the groove or mortise and the pocket are connected by a narrower groove 5, and in Figure 9 these elements are connected by an angularly disposed hole 6. In each case the pocket is designed to receive the knotted end of a sash cord which is passed through the groove or groove and hole.

By three successive operations of the machine the pocket 4 is bored with a boring bit; the channel or groove 3 is fashioned by the utilization of one or more rotary cutter heads; and when the secret or invisible hole 6 is to be bored, this is the final operation of the operating tools.

The main frame 7 of the machine is of generally rectangular shape and provided with a skeleton top or table 8, and the operating parts of the machine are driven from a belt 9 which transmits power from a suitable source to the driving pulley 10 on the transversely arranged power shaft 11 journaled in the main frame at the lower portion thereof.

The sash rails or blanks are furnished to the machine in uniform size and shape, and placed in a feed hopper located at the top of the machine and at one side thereof above the skeleton table top.

The feed hopper comprises fixed end brackets 12, side rails 13 and standards 14 fixed to the rails and elevated above the machine top to permit lateral movement of rails from the stack contained in the hopper. The standards 14 each have an outturned or curved upper end 15 to facilitate the entrance of the rails into the hopper for stacking between the oppositely arranged standards 14.

The fixed enclosure of the hopper is of

sufficient length to receive the maximum length of sash rails and the hopper is adapted for use with shorter lengths by utilizing the slidable bracket 16 which is slid-
5 able and supported by means of the block 16' on the inner tracks 17 of the side rails 13. The bracket may be slid longitudinally of the machine to compensate for various lengths of the rails to be operated on and
10 the rails are contained in the hopper in the form of a vertical stack from which the lowermost rail is intermittently pushed transversely of the machine.

As shown in Figure 3 the successive low-
15 ermost rails of the stack have been pushed or fed laterally of the machine at intermittent periods until a row of eight rails is seen on the machine top. The feeding device for this purpose includes a longitudinally extending push bar 18 located at the side of the machine below the main portion of the hopper and the push bar is designed to reciprocate laterally or transversely of the machine top. The pusher bar is provided at its ends with a pair of oscillating arms 20 fixed to a rock shaft 21 which is journaled in bearings 22 at the side of the machine.

The inward swinging movement of the
30 arms 20 and also of the pusher bar is limited by the use of stops 23 in the form of bolts in the arms that will contact with the side frame 24 to stop the pusher bar at the proper position after pushing the lowermost
35 rail from the stack in the hopper.

The horizontal rock shaft of the pusher or feed mechanism is actuated through a lever
25 fixed at one end to the shaft and at its other end pivoted to the adjustable rod 26
40 extending downwardly and pivoted at 27 on the horizontally disposed weighted arm 28. This lever arm 28 is provided at its free end with a weight 29 and is pivoted at 30 to the main frame of the machine in such manner
45 that the weight 29 will normally hold the pusher bar 18 in retracted position, and after a forward or working stroke of the pusher bar to feed a rail, the weight returns the pusher bar to retracted position.

50 The lateral working stroke of the feed bar or pusher bar is caused by depressing the free end 31 of the lever arm 28 through the action of an anti-friction roller 32 carried by a cam 33 on the cam shaft 34 which shaft
55 extends transversely of the machine and is journaled in the machine frame near its lower portion.

The cam shaft is revolved through its
60 pulley 35, belt 36 and pulley 37, the latter being fixed to revolve with the countershaft 38. The shaft 38 is driven from the shaft 38 by means of pulley 39 thereon and the belt 40 which passes over pulley 41 on the shaft 38 (see Fig. 4). As the rails in a
65 row are moved laterally and intermittently

by the push bar 18 they are held down and retained in horizontal position on the cross bars 2' of the machine top by means of a presser bar 42, which extends transversely of the machine and overlaps the row of
70 rails while they are being worked upon during the formation of the pocket and grooves.

This presser bar is urged downwardly by continuous pressure to prevent the rails from rising, and is supported from the
75 standard 43 fixed at the end of the machine frame 1. At the upper end of this standard a yoke 44 is provided in which are two springs 45 and 46, the lower spring 46 being the stronger and both springs exerting
80 pressure on the interposed head 47 of a lever arm 48 which is pivoted at 49 in the fixed bracket 50. To the lever arm 48 is rigidly attached a pressure arm 51 from which the presser plate 42 is suspended by
85 means of a pivoted link 52, and a guide link 53 pivoted in the fixed bracket 54 is also pivoted to the presser plate to hold it in operative position. By means of the presser plate the row of rails is held or retained under resilient pressure as the rails are fed laterally on the bars 2' and acted upon by
90 the machine tools as will be described.

The lateral movement of the row of
95 rails is controlled by means of a plurality of movable abutments or detents arranged transversely of the machine and adapted to engage the outer side of the forward rail of
100 the row, and intermittently actuated to release each succeeding completed rail and remove said rail for its discharge.

One of these oscillatable detents is illustrated in Figure 7 where an arm 54' is shown carrying at one end an antifriction roller 55 for contact with the side of the first rail. The detent arm is slotted at 56 for connection by bolt 57 to a base plate 58 beneath the arm, and this base plate which is disposed transversely of the rock bar 59 is fixed to rock therewith. The detent arm is slidable relatively to the base plate, and a coiled spring 60 has its respective ends attached to the two members 54' and 58 of the detent to exert its tension to move the
105 detent arm in the path of the laterally moving row of rails. When depressed to dotted position in Figures 2 and 3 this roller permits the discharged rail to ride thereupon and the completed rails are thus lifted by
110 two or more detent arms to position so that they may be transferred over cross bars 61 on the machine bars 2' and disposed of in
115 suitable manner.

The roller-ends of the detent arms are
120 depressed by actuation of the longitudinally extending rock bar 59 which is journaled in bearings 62 of the machine top 8. The rock bar is oscillated or rocked at predetermined intervals to swing the detent arms through
125 the use of a bracket 63 on the bar and a ver-
130

tically arranged lifting rod 64 attached thereto, which bar is attached to and raised by a longitudinally extending frame bar 65.

The frame bar is elevated by movement 5 started from the cam 66 on the cam shaft 34 which cam co-acts with a roller 67 journaled at the lower end of a rod 68 which is pivotally supported or suspended by a link 69 from the bracket 70 shown in dotted lines 10 in Fig. 4.

The rod 68 extends upwardly and is pivoted to the frame 71, and a rod 72 (Fig. 3) connects frame bars 71 and 65. When frame 15 71 in Fig. 4 drops, due to the action of the rotating cam 66 the rock bar 59 is oscillated to lower rollers 55 to dotted position in Fig. 3 which permits the rail at the left in said figure to move over on top of the roller end of the detent arms. Then by action of the 20 virtually revolving cam 66 the arm and rail are lifted to position to permit transfer of the rail to the discharge guides 61 on the cross bars 2'.

The two bits 73 and 74 which bore the 25 pocket 4 and the end of the groove 3 are operated in unison and simultaneously by the gears 75 and 76 and driven from shaft 11 by pulley 77 and belt 78, which belt is twisted around pulley 79 of the boring shaft 80. These boring tools are disposed at an 30 angle as shown in Fig. 1 and are supported on a plate 81 which is slidable in the fixed frame 82. The boring head or slide plate 81 is actuated from the cam 33 on the cam shaft 34, by means of a cam roller 83 bearing on the cam and the arm 84 which carries the roller and brace bar 85 both of which are fixed to the slide plate or head 81. These 35 two boring tools are elevated to bore the holes in the rail from the underside, and are then lowered to permit change in the position of the bored rail with each revolution 40 of the cam 33 of the shaft 34.

After the pocket has been bored the rails 45 are moved laterally to present the bored rail for action by two rotary cutter heads 86 and 87, the former to cut the wide groove 3 and the latter to cut the narrow groove 5 when the narrow groove is used. 50 The cutter heads have both a vertical movement for cutting the proper depth of groove and a movement longitudinally of the machine to cut the longitudinally extending grooves, and the cutter heads are located 55 at one side of the boring tools 73 and 74.

These cutter heads are carried on a sub-frame 88 having a screw 89 for lateral adjustment and screw 90 for adjusting it vertically. Power for driving the cutter heads 60 is taken from the pulley 91 by belt 92 to the pulleys of the cutter heads indicated at 93. The transmission pulley 91 is driven from the shaft 11 by sprocket chain 94 and sprockets 95 and 96. Pulley 91 is adapted to 65 swing with its frame 97 on shaft 11 as a

center with carriage 98, by action of the lever arm 99 which is pivoted at 100 to the machine frame at its opposite end. The lever arm is swung on its pivot by action of the eccentric 101 on the cam shaft 34 and link 102 pivoted to the arm 99. At 103 the lever arm is connected to the reciprocable carriage. Thus as the carriage is reciprocated longitudinally of the rail it also is given a vertical movement to insert and 70 force the cutter heads into the rail by the cam 66 and its connections as described.

The secret or invisible hole 6 connecting the pocket and the groove or channel in the rail is sometimes substituted for the narrow 80 channel 5 and this hole is bored with a bit 104.

As seen in Figure 6 this bit 104 is actuated from the cam shaft 34 through the revolving cam 105, the bit being located above the 85 machine top with its slidable shank 106 journaled in fixed bearings 107. The driven pulley for rotating the bit indicated at 108 is driven by the belt 108^a from the electric motor 108^b, but the movement of the bit is controlled, as are the other boring and cutting tools, from the cam shaft 34. A collar 109 on the bit shank is supported on the head 110 of a lever arm 111 which is pivoted at 112 on the machine frame. This lever arm 90 has a weight 113 at its free end and below the weight at the extremity of the arm a horizontally disposed link 114 is pivoted which slides and is guided between the anti-friction guide rollers 115 journaled on the 95 machine frame, one above and one below the link. At its free end this link is provided with a cam roller 116 for co-action with the cam 105 on the cam shaft 34. By action of the cam 105 the lever arm 111 is swung as indicated by dotted lines in Fig. 1 to cause the bit to advance and bore the secret hole 100 in the rail, and by means of a retracting spring 117 the lever arm is swung to withdraw the bit from the rail.

Thus from the single cam shaft 34 the rails in a row are intermittently moved step by step laterally of the machine. In first position the rail is bored for the pockets by the drills 73 and 74; in its second position cutter head 86 may channel out the wide groove; and in third position the bit 104 may bore the invisible hole, in which case the cutter head 87 is not used.

When both cutter heads 86 and 87 are used for cutting the two grooves, the bit 104 is disconnected and not used. Thus the rails are moved and a boring and cutting operation take place with each revolution of the cam shaft. And the row of rails is intermittently moved step by step, each succeeding completed rail being picked up by two or more of the detents for transfer to the discharge rails 61 as described.

Having thus fully described my invention,

what I claim as new and desire to secure by Letters Patent is—

1. The combination in a woodworking machine with its top and a hopper for a vertical stack of rails, of means for intermittently feeding the lowermost rails to form a horizontal row, a transversely disposed suspended retaining plate for said row, a lever arm pivoted to said plate and springs 10 engaging said arm for normally holding the plate in contact with said row of rails, a pivoted discharging arm for controlling the lateral movement of said row of rails, and means for actuating said arm to successively 15 remove completed rails.
2. The combination in a woodworking machine with its top and a hopper for a vertical stack of rails, of an operating shaft, feed mechanism for intermittently moving the lowermost rails to form a horizontal row, 20 means for retaining said row against vertical movement and resilient means for actuating said retaining means, means for controlling the lateral movement of the row of rails, connections from the operating shaft to said feed mechanism, and connections 25

from said shaft to said control means whereby the latter is actuated to successively remove completed rails from the row.

3. In a woodworking machine adapted to feed rails in a row, the combination of a rock bar and actuating means therefor and a transversely disposed base plate fixed to said bar, a spring pressed detent arm carried by said base plate for controlling the movement of said row of rails and adapted to be depressed to release and support a rail, and means whereby said arm is moved to lift a completed rail from said row.

4. In a woodworking machine adapted to feed rails in a row, the combination of a rock bar and a transversely disposed base plate fixed thereto and provided with a bolt, of a slotted and spring pressed detent arm carried by the base plate for controlling lateral movement of said row of rails and adapted to be depressed to release and support a rail, and means for actuating said rock bar whereby said arm is moved to lift a completed rail from said row.

In testimony whereof I affix my signature.

DONALD H. HERBERT.
